NECKTIE RACK OR SIMILAR ARTICLE

Eugene N. Tomlinson, Wichita, Kans.

Application June 18, 1954, Serial No. 31,067

Term of patent 14 years

(Cl. D33—8)

Fig. 1 is a three-quarter front perspective view of a necktie rack, embodying my new design; and

Fig. 2 is a side view of the left hand side of the rack shown in Fig. 1.

The hanger element shown at the lower end of the rack, in Fig. 2, is substantially identical to the hanger element at the upper end of the rack, as clearly shown in both drawing figures.

I claim:

The ornamental design for a necktie rack or similar article, as shown and described.
